CLAIM

The ornamental design for a multi-faceted miniature light bulb glass envelope, as shown and described.

DESCRIPTION

FIG. 1 is a front elevational view of a multi-faceted miniature light bulb glass envelope showing my new design, with the environment being illustrated in phantom line, and the back being a mirror image thereof;

FIG. 2 is a side elevational view thereof, the opposite side being a mirror image thereof;

FIG. 3 is a top plan view thereof; and,

FIG. 4 is a bottom plan view thereof.

The base of the lamp is shown in broken lines for illustrative purposes only and forms no part of the claimed design.
